UNITED STATES PATENT OFFICE.

MARK THOMAS DENNE, OF EDGEHILL, WARLINGHAM, ENGLAND.

MICROTOME.

Application filed October 19, 1920. Serial No. 418,086.

To all whom it may concern:

Be it known that I, MARK THOMAS DENNE, a subject of the King of Great Britain, residing at Edgehill, Warlingham, in the county of Surrey, England, have invented a new and useful Improvement in Microtomes, of which the following is a specification.

This invention has reference to improvements in and relating to microtomes, and in particular to that type of such machine in which the "subject" or mass to be cut into extremely thin sections for anatomical and biological purposes and the like, is reciprocated in the vertical plane relatively to a stationary knife.

Although machines of the aforesaid type are generally preferred, they are not by any means satisfactory as heretofore constructed, notwithstanding that those engaged in designing such machines are well aware of the difficulties of the problem and which will be at once apparent if one contemplates that the "subject" or mass has frequently to be cut into sections of .001 mm. thickness.

As a result of a good many experiments and careful tests I find that when using machines of the aforesaid type there is at times a considerable variation in the thickness of the sections cut, not only when different sections cut are compared but even in the thickness of different portions of each individual section (of course the term "considerable" has to be construed in the light of the extremely fine measurements that have to be made).

This want of regularity is, I find due to various causes. Firstly the mass to be sectioned is carried in a holder that is mounted on a slide or carriage which is made to travel in the horizontal direction to feed the mass relatively to a stationary knife, the carriage being in turn supported by a vertical slide which is made to reciprocate on a post. By reason of there thus being two slides, the work holder overhangs or projects away from the rigid post a considerable distance and this itself produces a want of rigidity that seriously affects the quality of the work performed. Further as the carriage carrying the work or mass holder is constantly (intermittently) being fed forward, the overhang increases, thus increasing, to the extent of the increase in the overhang, the want of rigidity. Further, also, the micrometer feed device is also

carried by the vertically reciprocating slide to impart intermittent feed movement to the horizontal work clamp-carrying slide, thus increasing the weight or mass to be reciprocated which also serves to disturb the evenness of balance in the moving parts.

Whilst the aforesaid defects might be of no real moment in many classes of machines, when they exist in microtomes they become very serious owing to the extreme thinness of the sections to be cut.

Another defect I find is that it is almost impossible in the machines in use, to effect that precise and accurate adjustment of the angle of the knife which, I find, is absolutely necessary if satisfactory cutting of different "subjects" and varying thicknesses of sections are to be cut.

The object of my invention is to obviate the aforementioned defects, my invention comprising, further, certain useful improvements in details of the machine.

To these ends my invention consists in a microtome having in combination a vertical post projecting from the base of the machine, a work clamp-carrying slide to be reciprocated thereon, a micrometer feed carried by the base and a knife moved intermittently along the base.

My invention, further, comprises, as important features, an improved feed regulating mechanism whereby any desired thickness of sections (within the compass of the machine) may be obtained; and also means for enabling a very precise angular adjustment of the knife to be obtained.

I wish it to be understood that my invention is not limited in its scope to the particularly constructional form hereinafter described and illustrated in the accompanying drawing, although that form in itself is a valuable feature of my invention.

In the accompanying drawings Fig. 1, is a side elevation of the machine, the position of the knife and its holder being merely indicated by broken lines. Fig. 2, is a front elevation, the knife and the subject holder being removed. Fig. 3, is a plan view of only the base and its slide, and with the column in section. Figs. 4, and 5, are a side elevation and sectional plan of the subject holder; and Figs. 6, and 7, are a side and front elevation, respectively, of the knife holder, the knife being removed.

In said drawings A indicates the base of the machine which will be made somewhat

heavy to ensure rigidity. Upstanding from said base is a vertical column B, of approximately triangular shape in cross-section, and having accurately machined slide-ways at its angles or corner parts. Adapted to slide on said column is a carriage comprising parts C, C', which may be adapted so as to snugly fit on the column by set screws c, c, and by means of which any wear that takes place 10 may be taken up.

In order to ensure that the part C shall at all times fit snugly yet firmly against the column, I provide an antifriction roll R that is mounted to rotate on a pin r projecting from an eccentric shank r', so that by 15 rotating the latter in its bearing on the part C' the roll R can be brought to bear firmly against the column B and by this the part C is drawn against the column so that there is 20 not the least danger of any slack or looseness between them. The shank and pin are made of suitable material so that the pin r has a certain amount of spring which will 25 materially assist in maintaining the desired firm contact of the part C with the column. The shank r' after the adjustment has been effected for the purpose stated, is clamped in position by a set-screw r².

For imparting to the carriage the necessary 30 vertical reciprocations, I provide a shaft S, supported in suitable bearings in the base A, on the outer end of which I provide a balanced handwheel s, if the machine is to be hand operated, or a pulley if 35 it is to be driven by power. On the other end of the shaft I provide a crank s', the crank pin p of which is provided with a connecting rod s² which latter is also pivotally connected to the carriage by a pin p'.

The part C of the carriage is provided 40 with a clamp D that carries the cylindrical stem d of a support d' which is to carry the subject holder d². The latter has a fixed jaw e and a movable jaw e' which is adjusted by 45 a screw e² to hold or grip the subject to be sectioned. The holder d² has a segmental web f having a flange f' which is embraced by the suitably shaped bifurcated end of a draw-bar f². The latter passes through an 50 aperture in the washer f³ which fits in a recess on the cylindrical stem d, and its outer end, which is screw-threaded is provided with a nut f⁴. By the foregoing construction and arrangement of the parts, by slackening the nut D' so as to loosen the grip of 55 the clamp D on the stem d, the holder d² can be turned around a horizontal axis, and by slackening the nut f⁴ the holder d² can be moved or swung around a vertical axis. 60 That is to say the holder can be adjusted so that the subject can be sectioned at any desired angle, the nuts f⁴ and D' being, of course, tightened up when the desired adjustments have been made. The foregoing 65 forms a very rigid support and yet the ad-

justments as aforesaid can be easily and quickly effected, and further, the parts can be readily dismantled as and when this is necessary. The carriage may be clamped in any position by means of the screw t² act- 70

The knife, indicated at H in Fig. 1, is carried in a holder (shown in detail in Figs. 6 and 7) consisting of two cylindrical discs h, h', connected by a stem h². The said discs are slotted at h³ to receive the ends of the knife and the latter is clamped firmly in 75 position by setscrews such as h⁴, Fig. 6.

The said discs are carried in bearings i, i', 80 on a block i² which is adjustably mounted on a micrometer slide T, being engaged in a slot t therein, by a T bolt i³ entered in the undercut slot in the slide and which bolt can be tightened up by screwing up the screw i⁴ which has a part i⁵ of its shank tapering and which part engages against a correspondingly shaped inclined surface or wedge i⁶ in the head of the T bolt i³. The arrangement described enables the knife and 85 its holder to be easily removed from the 90 slide.

One of the discs (h') has a snug m one side of which is pressed against by a spring m', which will rotate the knife holder if the set screws m² are slackened, and on the opposite side is acted on by an adjusting screw m³ so that by screwing the latter in or out the holder will be rotated in its bearings and thereby the angle of the knife will be 95 regulated according to the nature or character of the subject to be sectioned. The means just described enable a very fine or precise and accurate adjustment of the angle of the knife to be effected, this being a matter of very great importance when various different materials or substances have, 100 from time to time, to be cut into sections as thin as .001 mm. When the desired adjustment has been effected, the holder is 105 clamped tight by the set screws m².

The micrometer slide T is made of solid construction so as to be perfectly rigid, and it is mounted in suitable guide-ways t' on the base of the machine. Said slide is moved by the micrometer screw t³ (Fig. 1) 110 the nut t⁴ of which is attached to one end of the slide whilst the end of the screw abuts on a foot t⁵ rigidly attached to the base.

The micrometer screw is rotated by means 115 of the large ratchet wheel L which is mounted thereon in such a manner, for example frictionally, so that by slackening back a nut l the wheel is freed from the screw so that the latter may be rotated by merely rotating the milled head l' and thus avoiding having to rotate the large ratchet wheel as and when a rapid setting back or forward of the slide T and the knife thereon is required. There are so many known ways in which 120

such a connection and disconnection of the ratchet wheel and its micrometer screw can be effected that detailed description of any one way is not deemed to be necessary and 5 would merely lead to confusion if incorporated in the drawing.

To effect the intermittent rotation of the ratchet wheel, I provide two pawls l^2 l^3 (one being one half a tooth shorter than 10 the other) which are pivoted at the free end of a lever l^5 that is fixed at its other end to one end of a rock shaft l^4 which is supported in suitable bearings. On the 15 other end of the rock-shaft is fixed a two armed lever having arms l^6 and o , one arm l^6 of which has a pin l^9 that is engaged in a slot in the lower end of a vertical rod l^8 , the upper end of which rod is slideable in 20 a groove in the vertical post B (see more particularly Fig. 1).

Carried by the part C' on the post B, is a bearing for a pin l^9 having an eccentric l^{10} that enters a long slot l^{11} in the rod l^8 . The pin l^{10} will rise and fall with the part 25 C' as the connecting-rod s^2 imparts movement, as already described and the slot l^{11} in the rod l^8 is long enough to permit of this.

The weight of the rod l^8 and of the levers l^5 , l^6 , on the rock-shaft l^4 will cause the said 30 rock-shaft to turn in the direction to bring the pawls down relatively to the ratchet wheel L, the pawls, or one of them engaging in a fresh tooth in the wheel. (Springs r act to bring the pawls into engagement 35 with the teeth.) When next the part C' is raised, the pin l^{10} will contact with the upper end of the slot l^{11} in the rod l^8 and will lift the latter this in turn rocking the shaft l^4 and causing its lever l^5 to lift the pawls 40 and rotate the ratchet wheel and thus impart movement to the knife carrier and knife.

In order to limit the extent of the aforesaid movements, I provide means to adjustably limit the upward movement of the 45 arm o of the said two armed lever, and thus, to a corresponding extent, limit the downward movement of the rod l^8 and pawls l^2 , l^3 .

The means I provide for the purpose aforesaid, consists in a vertical cylinder o' adapted to be rotated in a suitable bearing. The lower end of this cylinder is formed with a number of steps o^2 all at progressive 55 different altitudes, and these steps are adapted to form stops against which a pin o^3 on the lever o will contact. Accordingly therefore, as the cylinder o' is set so will the extent of the upward movement of the lever o and consequently, through the mechanism 60 already described, of the downward movement of the pawls l^2 l^3 be determined.

As shown in Fig. 2, the cylinder is set 65 to permit of the very minimum of movement of the lever o . This may be such that the

two pawls l^2 l^3 will set alternately to advance the ratchet wheel through the distance of one half of one of its teeth, and at this rate the micrometer screw will advance the knife so that sections of .001 mm. thickness will be cut. If the cylinder be provided with say twenty steps o^2 each progressively permitting an increase in the feed movement of the knife of .001 mm., the machine will have a range from .001 mm. to .02 mm. 70

In order that the operator may easily determine what thickness of section is to be cut, I provide the top of the cylinder with a gauge or scale o^4 , and a milled knob o^5 . 80

The part l^{10} of the pin l^9 (see Fig. 1) is made eccentric so as to enable exact adjustment to be effected.

In order to prevent accidental over-running of the slide T, if the operator, after 85 sectioning several successive blocks of material, should fail to again set back the slide T and the knife, I provide a brake device. This may consist of a rod r on the slide and a rod w' on say the frame of the machine, 90 or carried by the part C'. Or any other suitable braking device may be employed.

The ratchet wheel will be enclosed by a casing or cover w^2 and I may provide a 95 spring Q to take up back-lash.

I claim:

1. In a microtome, the combination with a base, of a post rising therefrom, a carriage held against and slideable vertically on the post, a subject-holder mounted on the carriage, a slide mounted on the base, a knife supported by said slide, a feed screw for feeding the slide, an operating shaft, connections between said shaft and said carriage, and means to actuate the feed screw 100 from said shaft.

2. In a microtome, the combination with a base, of a post rising therefrom, a carriage slideable vertically on the post, a subject-holder sustained by said carriage, a slide on the base, a knife supported by said slide, a feed screw for actuating the slide, an operating shaft, connections between said shaft and slide, and micrometer pawl and ratchet mechanism for actuating the feed screw 105 from said shaft.

3. In a microtome of the type described in claim 2, the combination with said feed screw having a ratchet wheel thereon, a rocking lever carrying pawls to actuate the ratchet wheel, means to actuate the lever from the shaft, a pin on said lever, and a rotatable cylinder provided with stop shoulders at its end to engage said pin thereby to limit the oscillating movement of the lever. 115

4. In a microtome, the combination with a base, of a column rising therefrom, a subject-holder supported to slide vertically on said column, a slide mounted on the base, a knife-holder carried by said slide, and a 120

125

130

micrometer feed mechanism located in the base for giving movement to the slide.

5. In a microtome, the combination with a base, of a column rising therefrom, a subject-holder supported to slide vertically on said column, a slide mounted on the base, a knife-holder carried by said slide, and a micrometer feed to impart intermittent movement to said slide.

10 6. In a microtome, the combination with a base having ways, of a slide slidable in said ways, a knife support carried by said slide, a rotatable knife-holder sustained by said support, a spring device tending to rotate the holder in one direction, a screw device by which it may be turned in the opposite direction, and means to lock the holder on its support.

20 7. In a microtome, the combination with a base, of a column rising therefrom, a subject-holder slidable on said column, a knife-support slidable in said base relative to the column and holder, and a micrometer screw feed device acting directly on said knife support.

30 8. In a microtome, the combination with a base having ways, of a slide operating in said ways, a column rising from the base, a bearing slidably mounted on the column, a subject-holder carried by the bearing, spring-actuated means to maintain the bearing firmly in contact with the column, and a knife-holder carried by the slide.

35 9. In a microtome, the combination with a base having ways, of a slide mounted in

said ways, a knife support carried by said slide, and a wedge device to cramp the support to the slide.

10. A microtome of the type referred to having in combination a base, a slide bearing in said base, a micrometer feed screw connected to said bearing and located within the base, a driving spindle, rocking levers carried by said spindle and means operated by said levers to impart intermittent rotation to said screw.

11. In a microtome of the type referred to, the combination with a base, a column rising from said base and a carriage slidable thereon, of a subject-holder carried by said carriage and devices for adjusting and locking the holder relative to the carriage.

12. In a microtome of the type referred to, the combination with a base, a column rising therefrom, and a carriage slidable thereon, of a subject-holder carried by said carriage and devices for adjusting the holder around axes at right angles to each other.

13. A knife-holder for microtomes embodying a knife support that is rotatable in said holder, a cramping device to fix the knife in said support, a spring acting to rotate the support in one direction, a screw to rotate the support in the opposite direction, and a cramping device to clamp the support in the holder.
